UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

TAKE-DOWN GUN.

964,974.

Specification of Letters Patent. Patented July 19, 1910.

Application filed May 23, 1910. Serial No. 563,008.

To all whom it may concern:

Be it known that I, THOMAS C. JOHNSON, a citizen of the United States, residing at New Haven, in the county of New Haven 5 and State of Connecticut, have invented a new and useful Improvement in Take-Down Guns; and I do hereby declare the following, when taken in connection with the accompanying drawings, and the characters of 10 reference marked thereon, to be a full, clear, and exact description of the same, and which said drawings constitute part of this specification, and represent, in—

Figure 1 a broken view partly in left 15 hand side elevation and partly in vertical section of a gun constructed in accordance with my invention. Fig. 2 a broken view of the breech-block in horizontal section on the line *a*—*b* of Fig. 1 and showing the 20 locking-lever pushed by the action-bar into its retired position for releasing the breech-block. Fig. 3 a corresponding view showing the locking-lever in its locking position in which it holds the breech-block in its 25 elevated and locked position, this view showing a portion of the receiver in horizontal section. Fig. 4 a broken view in vertical section on the line *c*—*d* of Fig. 3 and looking from front to rear in the direction of 30 the arrow *e*. Fig. 5 a detached view in outside elevation of the locking-lever. Fig. 6 a broken plan view of the rear end of the action-bar.

My invention relates to an improvement 35 in repeating take-down guns of that class having a longitudinally movable breech-block which is raised and lowered at its rear end for being locked and unlocked, and operated by its connection with the rear 40 end of an action-bar the forward end of which is secured to a sliding handle located in front of the gun-frame or receiver and moving back and forth under the gun-barrel, the object of my present invention being to 45 provide a simple and reliable mechanism for holding the breech block in the gun-frame when the gun is taken down, and for unlocking the breech-block when the gun is put together.

With these ends in view my invention consists in a repeating take-down gun having certain details of construction as will be hereinafter described and pointed out in the claims.

In carrying out my invention as herein

shown, I employ a locking-lever 2 located in a deep horizontal recess 3 formed in the left hand side wall of a longitudinally and vertically movable breech-block 4 which is formed at its rear upper corner with a 60 locking-nose 5 entering a locking-notch 6 formed in the inner face of the solid top 7 of the gun-frame or receiver 8 to the forward end of which the gun-barrel 9 is removably connected on any approved take-down principle. As shown, the barrel 9 is connected to a take-down band 10 the lower portion of which has an opening (not shown) for the rearward passage through it of the tubular magazine 11 the forward 70 end of which is supported by the barrel. The said locking-lever 2 is pivoted upon a vertical pin 12 passing through an eye 13 formed near the forward end of the lever the extreme forward end of which is shaped 75 to form a stop-finger 14. To adapt the lever 2 to discharge its locking function, it is formed with a locking-rib 15 projecting outwardly from its outer face and adapted to enter a horizontal cut 16 formed in the inner 80 face of the left hand wall of the gun-frame or receiver 8, the lever being swung outwardly upon its pivot 12 by means of a helical spring 17 located in a socket 18 leading out of the bottom wall of the rear end 85 of the recess 3 in the breech-block 4, the said spring 17 exerting a constant effort to swing the outer end of the lever outward.

To retire the lever 2 so as to release the breech-block, I provide it with an outwardly projecting operating-cam or bevel 19 located upon the lower edge of its rear end in position to be engaged by the rear end of the horizontal action-bar 20 which moves back and forth in a shallow groove 21 located below the cut 16 aforesaid and formed in the inner face of the left hand wall of the gun-frame or receiver 8, the said action-bar being secured at its forward end to an operating-handle 22 mounted for sliding 95 movement back and forth upon the magazine 11 in the usual manner. An operating-lug 23 projecting inward from the action-bar 20 enters a cam-path 24 formed in the left hand side wall of the breech-block 4, the said 105 cam path being adapted in form to cause the action-bar to move the block 4 back and forth and also to raise and lower the block into its locked and unlocked positions when it is at the limit of its forward movement. 110

Under ordinary conditions, the locking-lever 2 will be maintained in its retired position in which it is idle, by the engagement of the high point of its cam 19 by the flat 5 inner face of the action-bar 20. When the gun is taken down, the action-bar 20 is removed with the gun-barrel 9, magazine 11 and band 10, from the gun-frame 8 and the parts organized therewith. As the said bar 10 20 is drawn forward out of its groove 21, it is disengaged from the lever 2 which is at once swung outward so as to enter its locking-rib 15 into the cut 16 in the gun-frame 8, by its spiral spring 17 which will 15 maintain it in its locked position as long as the gun is taken down at which time the block 4 will be held in its elevated and locked position in the said gun-frame. When, however, the gun is put together, the 20 extreme rear end of the action-bar 20 will ride over the cam 19 of the locking-lever 2 and swing the same inward against the tension of its spring 17, whereby the locking-rib 15 of the lever 2 will be entirely cleared 25 from the cut 16 and the block permitted to be raised and lowered again by the action-bar as though the said lever were not present in the gun.

I claim:

30 1. In a take-down gun, the combination with the frame thereof, of a longitudinally and vertically movable breech-block, a sliding operating-handle, an action-bar extending rearwardly from the said handle and

connected at its rear end with the breech-block for the operation thereof, and a locking-lever for locking the breech-block in its elevated position, at the time the gun is taken down, the said lever being provided with a cam which is directly engaged by the 40 action-bar when the gun is put together for the retirement of the lever into its unlocked position.

2. In a take-down gun, the combination with the frame thereof, of a longitudinally 45 and vertically movable breech-block, a sliding operating-handle, an action-bar extending rearwardly from the said handle and connected with the breech-block for the operation thereof, a locking-lever located in a 50 recess in the breech-block, adapted to enter a cut in the gun-frame at the time the gun is taken down to lock the said block in its elevated and locked position, and provided with a cam which is directly engaged by the 55 rear end of the action-bar for retiring the lever when the gun is put together, and a spring for pushing the lever outward into its locking position when the gun is taken down.

In testimony whereof, I have signed this specification in the presence of two subscribing witnesses.

THOMAS C. JOHNSON.
